UNITED STATES PATENT OFFICE.

OSCAR DINGFELD, OF BROOKLYN, NEW YORK.

MACHINE FOR UNHAIRING FUR-SKINS.

1,287,914.

Specification of Letters Patent. Patented Dec. 17, 1918.

Application filed January 7, 1918. Serial No. 210,761.

To all whom it may concern:

Be it known that I, OSCAR DINGFELD, a citizen of the United States, residing at 125 Melrose st., Brooklyn, in the county of Kings and State of New York, have invented a new and useful Machine for Unhairing Fur-Skins, of which the following is a specification.

My invention relates to improvements in a machine for unhauling fur skins, and it consists in the novel features hereinafter more fully described.

The objects of my improvement are:

First, to reduce the amount of lost motion of the cutting blades and to counteract or reduce the effect of the looseness of the joints in the connections of said blades to the machine.

Second, to provide a means whereby the stubble of the clipped hair should be made of a uniform height or length, instead of making the stubble of the hair on the sides of the skin longer than in the center of the skin, as in machines of present design.

Third to provide automatically actuated shields or guards for parts of the skin, which it may be desirable to protect from the action of the cutting blades, said shields to be carried by the inner cutting blade or the carrier of said blade, as hereinafter described, and the position of said shields to be adjustable.

Fourth, to improve the operation of sundry parts of the machine in general and to have the machine simple durable and inexpensive.

I attain these objects by the mechanisms illustrated in the accompanying drawings or by any mechanical equivalent or obvious modification of the same.

In the drawings Figure 1 is a vertical section on the line A—B of Fig. 2 looking to the left; Fig. 2 is a vertical section on the line C—D of Fig. 1 looking to the right and omitting the stretcher bar or bridge and the brushes, which are shown in Fig. 1; Fig. 3 is a plan of my mechanism for making the stubble of the clipped hair of uniform length; Fig. 4 is a front view of the mounting of the above mechanism, omitting the combing plates and the means for controlling the same; Fig. 5 is a section on the line E—F of Figs. 3 and 4, showing also the stretcher bar or bridge of the machine and one of the adjustable shields in position; Fig. 6 is an end elevation of the connecting rod 40 of the

combing plates, showing the elongated slot 45 in the arm 42 of said connecting rod; Fig. 7 is a rear view of my machine for unhauling fur skins, looking to the left in Fig. 2, and showing the operating parts of the machine, but omitting the brushes and sundry other details.

Similar numerals and letters refer to similar parts throughout the several views.

11 designates the frame of the machine, to which I secure the pair of guides 12, which are shown in Figs. 1 and 7 as held at their ends in the sockets 14 of said frame by means of the set-screws 13.

Said guides 12 are fitted into a pair of slides or sleeves 15, which are shown in Fig. 2 as situated at the ends of the table or plate 23, which forms a movable support for the inner cutting blade 22.

Said table 23 may be made in one with said slides 15, and it is shown as strengthened by the vertical rib or web 24 on the underside thereof.

Said inner cutting blade 22 may be preferably inclined a few degrees, sloping downwardly to the right in Fig. 1, so as to permit the cutting edge of the outer cutting blade 21 to pass over it freely.

Each of said slides 15 is shown as carrying a bracket 16, which may be made in one therewith, and each of said brackets 16 terminates at its upper end in a bearing 17 for the spindle 18, which is shown as carrying the arms 19 and 19^a, which are made in one with the backing plate 20 of the outer cutting blade 21, which may be secured to said backing 20 in any suitable manner, and which is thereby adapted to revolve around said spindle 18 in the direction as indicated by the curved arrows in Fig. 1. Said arm 19 is placed ahead of said arm 19^a, and the backing plate 20 is inclined to the spindle 18; the cutting edge of said blade 21 is situated on a cylindrical surface, and it has, therefore, the outline of a helix, which outline may be given to it by grinding in the lathe the entire outfit of said blade 21 as connected to said spindle 18; the edge of said blade 21, which is adjacent to said arm 19, is the leading edge of said blade; and the edge of said blade 21, which is adjacent to said arm 19^a, is the follower edge of the blade.

Said inner cutting blade 22 is shown in Fig. 1 in the position as moving toward the stretcher bar or bridge 25, which is shown as having the conveyer 26 passing over its

crest, with the pelts or skins omitted, and the revolving and rocking brush 27 is shown in its downward phase of motion corresponding to the above position of said blade 5 22; the revolving brush 34 is also shown in position on the front side of said bar or bridge 25.

Said brushes 27 and 34 are shown as carried by the spindles 32 and 33 respectively, 10 of which the latter may be supported by the frame 11 of the machine, and the former is carried by the bracket 28, which is shown as pivotally connected to the oscillating link 29 by means of the pin 30; said link 29 may 15 be pivotally connected to the frame of the machine by means of the pin or spindle 31, and it serves to direct the motion of said bracket 28 and the revolving and rocking brush 27 in the required manner.

20 The outer blade 21 is shown as placed about 90° ahead of its correct position corresponding to the position of said blade 22, for the sake of illustrating the cutting action of the two blades, which will actually 25 take place when said blade 22 is at or near the upper edge of said bar or bridge 25, which is shown as placed at a distance therefrom, for the sake of clearness.

It is evident that, by supporting said 30 blade 21 from brackets, which are made in one with the support of said blade 22, there is only one joint to get loose and affect the correctness of the spacing of the cutting edges of said blades, and that is the joint 35 of the spindle 18 in the bearings 17; but that any looseness of the slides 15 on the guides 12 will not affect the distance between said blades. It is also evident that the same result would be attained whether 40 said blade 21 revolves on said spindle 18 through a complete circle or only oscillates through an arc of a circle.

The means for actuating said blades 21 and 22 and sundry other operating parts 45 of the machine are shown in Fig. 7 as follows:

The spindle 18 carries a sprocket, of 50 which the pitch line is designated as 52, which sprocket is operatively connected by means of the chain, the center line of which is designated as 50, to the sprocket 51, which is secured to the shaft 57, which carries the main driving pulley 59, which is adapted to receive power from a suitable belt; said 55 pulley 59 carries a crank pin 58, which operates the pair of bell crank levers 61—61^a by means of the pair of connecting rods 60; said bell crank levers actuate a pair of rocker arms 63 by means of the links 62.

60 Said rocker arms are each pivotally connected to the frame 11 by means of a stud 64, and they actuate said pair of sleeves or slides 15 hereinbefore described.

To take up the slack of said chain 50, 65 I provide the idler sprocket 53, of which the

spindle 70 is carried by the arm 54, which is pivotally connected to the frame 11 by means of the stud 56.

Said sprocket 53 is kept in contact with said chain 50, thereby stretching the same. 70 by means of the spring 55, which is shown as connected at one end thereof to the pin 68 in said frame 11 and at the other end to the pin 69 in said arm 54.

My mechanism for making the stubble of 75 the clipped hair of uniform length is omitted from Figs. 1 and 2, for the sake of clearness; it is shown in Figs. 3, 4, 5, and 6, in which 35 designates the mounting for the combing plates 38, which are shown as 80 having formed at their inner edges the journals 37, which are adapted to swivel in the bearings 36, formed in the front part of said mounting 35, which is shown as situated at the front face of the blade 21, and 85 it may be fastened thereto by suitable securing means; said mounting may also be connected to any other part of the mechanism, which revolves around the spindle 18 with said blade 21.

Said bearings 36 are shown as open on the front of said mounting 35 to allow said plates 38 to pass therethrough and to be inclined in position to said blade 21 in such a manner as to tend to raise the hairs of 95 the pelt or skin, which hairs are naturally inclined sidewise toward the outer edges of the skin in order that these hairs may be clipped to uniform length.

The lower edges of said plates 38 are 100 shown in Fig. 5 as rounded off, so as not to interfere with the motion of the other parts of the machine during the revolution of said blade 21, and the lower parts of said plates 38 are shown as extending backwardly 105 under said mounting 35 to within a very short distance from said blade 21.

The number of said plates 38 may be much larger than as shown in Fig. 3, where ten plates are shown as consisting of two sets 110 inclined in opposite directions.

The extent of the inclination of said plates 38 is controlled by the connecting rods 40, shown as having each an arm 42 at right angles thereto, said arms being adjustably 115 connected to the ends of said mounting 35 by means of the long screws 43 and the springs 44; said arms 42 are shown in Fig. 6 as provided with elongated slots 45 to allow for the component of the motion of 120 said arms in a direction crosswise to said screws 43 when adjusting the position of said plates 38 by means of said connecting rods 40, which are shown as pivotally connected to said plates by means of the sockets 125 41 on said rods 40 and the pins 39 on said plates 38; the caps 46 are shown in Fig. 5 as keeping said rods 40 in place on said plates 38.

Fig. 5 shows also one of my shields or 130

guards 48 as connected to a sliding plate 47, which has a tongue 49 adapted to slide in a corresponding groove on the underside of the inner blade 22, transversely thereto.

5 The object of said shield 48 is to protect any part of the furskin, which does not have to be unhaired, such as the sides of the skin, from having its fur cut by the blades 21 and 22, or from having portions of wrinkled 10 skin cut or mutilated. Any convenient number of such shields 48 may be employed, and their position with relation to any part of the skin or pelt may be adjusted by sliding said plate 47 transversely to said blade 22; 5 said shields may also be removed, if desired.

20 The forward end of said shield is shown in Fig. 5 as adapted to pass over said conveyor 26 on said bridge 25 slightly below the level of the cutting edge of said blade 22, thereby protecting the hair or fur on any skin or the skin itself from being cut.

25 Many changes could be made in my machine for unhauling furskins without departing from the main scope of my invention. I do not therefore restrict myself to the details as shown; but I intend to include also all mechanical equivalents and reasonably obvious modifications of the same within the scope of my invention.

30 What I claim as my invention, and desire to secure by Letters Patent is:

1. In a machine for unhauling fur skins a bridge bar for stretching the fur skins thereover, an outer blade and an inner 35 blade, a movable support for said inner blade and a bracket for said outer blade, said bracket being mounted on said support of said inner blade and said support being adapted to have a to and fro motion 40 with relation to said bridge bar.

2. In a machine for unhauling fur skins a bridge bar for stretching the fur skins thereover, an outer blade and an inner blade, a movable support for one of said 45 blades and a bracket for the other of said blades, said bracket being mounted on said support, and said support being adapted to have a to and fro motion with relation to said bridge bar.

50 3. In a machine for unhauling fur skins a bridge bar for stretching the fur skins thereover, an outer blade and an inner blade, a movable support for said inner blade and a bracket for said outer blade, 55 said support with said inner blade being adapted to have a to and fro motion with relation to said bridge bar, said support with said inner blade being stationary with relation to said bracket, and said outer 60 blade being adapted to move in an arc of a circle with relation to said support and said inner blade.

4. In a machine for unhauling fur skins a bridge bar for stretching the fur skins 65 thereover, an outer blade and an inner

blade, a sliding support for said inner blade and a bracket for said outer blade, said support with said inner blade being adapted to have a reciprocating motion with relation to said bridge bar, said support with said inner blade being stationary with relation to said bracket, and said outer blade being adapted to move in an arc of a circle with relation to said support and said inner blade. 70 75

5. In a machine for unhauling fur skins an inner blade and an outer blade, a bridge bar for stretching the fur skins thereover, thereby causing the coarse hairs of said fur skins to be raised preliminary to clipping, 80 a means for keeping down the fur of the skins, thereby eliminating said fur from the action of the blades, and a means for preventing said raised hairs from being inclined sidewise from the center of the skin, 85 thereby making the stubble of the clipped hair of uniform length across the width of the unhaired skin, said preventing means being adapted to act in conjunction with said outer blade and in advance of the operation thereof. 90

6. In a machine for unhauling fur skins an inner blade and an outer blade, a bridge bar for stretching the fur skins thereover, thereby causing the coarse hairs of said fur 95 skins to be raised preliminary to clipping, a means for keeping down the fur of the skins thereby eliminating the fur from the action of said blades and a means for preventing said raised hairs from being inclined sidewise from the center of the skin, 100 thereby making the stubble of the clipped hair of uniform length across the width of the unhaired skin, said preventing means being connected to said outer blade and 105 adapted to move therewith.

7. In a machine for unhauling fur skins an inner blade and an outer blade, combined with a set or sets of combing plates adapted to raise the inclined hairs of the fur 110 skins preliminary to clipping the same and thereby to make the stubble of the clipped hair of uniform length across the width of the unhaired skin, said plates being situated at the front of said outer blade, inclined 115 thereto, and adapted to act in conjunction therewith and in advance of the operation thereof.

8. In a machine for unhauling fur skins an inner blade, an outer blade and a set or 120 sets of combing plates, inclined to said outer blade, and adapted to raise the inclined hairs of the fur skins preliminary to clipping the same and thereby to make the stubble of the clipped hair of uniform length 125 across the width of the unhaired skin, said plates being situated at the front of said outer blade, combined with a means for regulating the inclination of said plates to said outer blade. 130

- 4
9. In a machine for unhairing fur skins an inner blade, an outer blade and a set or sets of combing plates, inclined to said outer blade and adapted to raise the inclined hairs of the fur skins preliminary to clipping the same, and thereby to make the stubble of the clipped hair of uniform length across the width of the unhaired skin, combined with a carrier for said plates, pivotally connected thereto, said carrier being situated at the front of said outer blade and adapted to move therewith, thereby causing said plates to act in conjunction with said outer blade, and a means for regulating the inclination 15 of said plates to said outer blade.
10. In a machine for unhairing fur skins an inner blade, an outer blade and two sets of combing plates, inclined to said outer blade and adapted to raise the inclined hairs of the fur skins preliminary to clipping the same, thereby making the stubble of the clipped hair of uniform length across the width of the unhaired skin, said plates being situated at the front of said outer blade and the inclination of the plates in each set being opposite in direction to that of the other set.
11. In a machine for unhairing fur skins an inner blade, an outer blade, two sets of 30 combing plates inclined to said outer blade and adapted to raise the inclined hairs of the fur skins preliminary to clipping the same, thereby making the stubble of the clipped hair of uniform length across the width of the unhaired skin, said plates being situated at the front of said outer blade, and the inclination of the plates in each set being opposite in direction to that of the other set; combined with a connecting rod 35 for each of said sets, said connecting rods being pivotally connected to said plates, and a means for adjusting the position of said connecting rods, thereby adjusting the in- elination of said plates to said outer blade, according to the degree and direction of in- elination of the hairs of the fur skins. 45
12. In a means for unhairing fur skins an outer blade and an inner blade for clipping the hairs of parts of the fur skins where such hairs are located, combined with one or more shields for protecting parts of the skin, which are not to be unhaired, and the fur thereon from being cut by said blades, said shield or shields being adapted to move with said inner blade and to be adjusted in 50 position transversely to the direction of its motion.
13. In a machine for unhairing fur skins an outer blade and an inner blade for clip- 60 ping the hairs of the parts of the fur skins where said hairs are located, combined with one or more shields for protecting parts of the skin, which are not to be unhaired, and the fur thereon from being cut by said blades, a carrier plate for each of said 65 shields, a groove on the underside of said inner blade transversely to the direction of its motion and a tongue on the upper side of said carrier plate, said tongue being slidably and detachably engaged in said groove, for 70 adjusting the position of the shield carried by said plate with relation to the fur skin, and means for causing said shield to move with said inner blade.
14. In a machine for unhairing fur skins 75 a bridge bar for stretching the fur skins thereover, an inner blade and an outer blade, a sliding support for said inner blade and a pair of brackets for said outer blade, said brackets being mounted on said sup- 80 port, said support with said inner blade being adapted to have a reciprocating motion with relation to said bridge, and said outer blade being adapted to revolve on a suitable spindle supported by said brackets.

OSCAR DINGFELD.
